UNITED STATES PATENT OFFICE

152,382

DESIGN FOR A CANDLE HOLDER

Virginia B. Tawresey, Philadelphia, Pa.

Application August 1, 1947, Serial No. 140,659

Term of patent 14 years

(Cl. D48—2)

To all whom it may concern:

Be it known that I, Virginia B. Tawresey, a citizen of the United States, residing in Philadelphia, county of Philadelphia, Commonwealth of Pennsylvania, have invented a new, original, and ornamental Design for Candle Holder, of which the following is a specification, reference being had to the accompanying drawing, which forms a part thereof.

I claim:

The ornamental design for a candle holder, substantially as shown.

VIRGINIA B. TAWRESEY.
